UNITED STATES PATENT OFFICE.

GEORGE F. ALBRECHT, OF WOONSOCKET, RHODE ISLAND, ASSIGNOR TO WOONSOCKET MACHINE & PRESS CO., INC., OF WOONSOCKET, RHODE ISLAND, A CORPORATION OF RHODE ISLAND.

TRAVELING-FLAT CARDING ENGINE.

Application filed May 10, 1923. Serial No. 638,069.

To all whom it may concern:

Be it known that I, GEORGE F. ALBRECHT, a citizen of the United States, residing at Woonsocket, in the county of Providence, State of Rhode Island, have invented a certain new and useful Improvement in Traveling-Flat Carding Engines, of which the following is a specification, reference being had therein to the accompanying drawings.

10 The invention is an improvement in the means of actuating the rotary clearer-brushes by which lint, etc., is removed from those portions of the backs of the traveling flats, at the ends of the flats, which make 15 contact with the guiding and supporting sheaves, and in some cases also from the links at the ends of the flats which join the flats together into an endless chain, and from the pivot screws connecting the links 20 to the ends of the flats. The invention is illustrated in the accompanying drawings, in which latter,—

Fig. 1 shows in side elevation certain portions of a traveling flat carding engine, with a preferred embodiment of the invention applied thereto.

Fig. 2 is a side view on a larger scale of the brushes of Fig. 1, the ratchet and pawl devices shown combined therewith, and portions of the brush-carrier and adjacent stripper-stand, the end brush being only partly shown.

Fig. 3 is a view, chiefly in section on line 3—3 of Fig. 2, of the parts shown in said figure.

Fig. 4 shows the pawl, pawl-carrier, and associated screws in disassembled relation.

Having reference to the drawings,—

The chain of traveling flats 1, Fig. 1, only 40 a portion of which is represented, is shown extended in usual manner around and over sheaves 2, 3, (only two of which are shown) mounted as usual upon shafts 21, 31, supported by brackets or stands 4, 5, that are 45 attached to the arch 7 in connection with the main cylinder, and project radially therefrom. At 15 is shown the usual stripper-blade or comb for removing fibrous material, etc., from the card-clothing of the 50 flats as they pass around the sheave 2 on leaving the surface of the main cylinder, at 14 one of the arms of a stripper-blade carrier, and at 13 the supporting rockshaft of the said carrier, such rockshaft being journaled 55 in a bearing provided in connection with bracket or stand 4 (herein termed also stripper-stand). The means for rocking the rockshaft to vibrate the stripper-blade is not shown; it may be in practice of any convenient character.

60 At 10 is shown one of the brushes which are employed for clearing lint, etc., from those portions of the backs of the flats which make contact with the sheaves 2, 3, in passing around the latter, and 100 is one of the 65 brushes employed for clearing lint from the links 9 joining the flats together into an endless chain, and from the pivot screws 70 connecting the said links with the flat ends. At 101 is the shaft to which the 75 clearer-brushes 10 and 100 are attached, and at 12 is one of the supporting arms, fixedly attached by clamping screw 120 to the rockshaft 13 of the stripper-carrier and having an open-topped bearing at 11 which receives the journal-portion of the brush-shaft 101. At 16 is a ratchet-wheel which is attached to the brush-shaft 101, and at 18 is a pawl which through engagement with the teeth of the ratchet-wheel 16 serves to 80 rotate the brush-shaft and its clearer-brushes 10 and 100.

85 The invention consists essentially in the combination with a clearer-brush for removing lint from the end-portions of the traveling flats of the traveling flat carding engine, and a brush-support that is movable relatively to the chain of traveling flats, of means actuated through the movement of the said brush-support to rotate 90 the said brush. In the illustrated embodiment of the invention, the said means includes a pawl-carrier which is vibrated as a result of the movement of the brush-support. Such pawl-carrier 17 is in this instance a lever with which the pawl 18 is connected by means of a pivot screw 181, the said lever having an open-bottom bearing 171 to receive and fit the journal-portion of brush-shaft 101, so as thereby to 100 mount the pawl-carrier concentrically with the clearer-brush and ratchet-wheel. The said pawl-carrying lever is engaged with an adjacent stationary part, which in this instance is for convenience constituted by a lateral extension of the stripper-stand 4 so that as the brush-support moves in rocking as previously mentioned, the pawl-

carrying lever is caused to vibrate or rock around the axis of the brush-shaft. The engagement of the pawl-carrying lever is effected in this instance by means of a screw 20 which is applied to and projects from the said lever so that its stem 201 occupies a slot 19 in the stripper-stand, this slot being of sufficient length to accommodate the movement of the said screw longitudinally 10 of the slot, which is incidental to the rocking or vibrating movement of the pawl-carrier, etc. For convenience in assembling and disassembling the parts, the slot 19 is made open-ended, accidental disengagement 15 of the stem 201 of screw 20 being prevented by means of the flange or head of a screw 21 that is applied to the end of the extension of the shipper bracket in such relations that a portion of the said flange or head 20 projects partway across the open end of the slot 19. The flange or head 202 of the screw 20 prevents accidental disengagement of screw 20 from slot 19 as a result of lateral displacement. The open-topped bearing 11 25 in supporting arm 12, the open-bottomed bearing 171 in pawl-carrier 17, and the open-ended slot 19 in the lateral extension of shipper bracket 4, provide for convenience and speed in assembling and disassembling 30 the parts.

I claim as my invention:—

1. In a traveling flat carding engine, the combination with a clearer-brush for removing lint from the end-portions of the traveling flats, and a brush-support movable relatively to the chain of traveling flats, of means actuated through the movement of the said support to rotate the said brush.
2. In a traveling flat carding engine, the combination with a stripper for the toothed clothing of the traveling flats, a vibrating carrier therefor, and a clearer-brush for the end-portions of the flats, supported by and moving with the said carrier, of means actuated through the movement of the brush and carrier to rotate the brush.
3. In a traveling flat carding engine, the combination with a rocking support, a clearer-brush journaled thereon, a ratchet-wheel combined with said clearer-brush and a pawl engaging said ratchet-wheel, of a pawl-carrying lever mounted upon a journal of the said clearer-brush and loosely engaging an adjacent part of the machine whereby the rocking movement of said support and brush produces movement of the lever and pawl which rotates the brush.
4. In a traveling flat carding engine, the

combination with a stripper for the toothed clothing of the traveling flats, a vibrating carrier for said stripper, a stripper-stand, a clearer-brush for the end-portions of the flats, supported by and moving with the said stripper-carrier, a ratchet-wheel connected with the said brush, and an actuating pawl 60 engaging said ratchet-wheel, of a pawl-carrier mounted upon a journal of the clearer-brush and engaged with the said stand so that the rocking movement of the stripper-carrier and brush produces movement of the pawl-carrier and pawl which rotates the brush.

5. In a traveling flat carding engine, the combination with a stripper for the toothed clothing of the traveling flats, a vibrating carrier for said strippers, a stripper-stand, a clearer-brush for the end-portions of the flats, supported by and moving with the said stripper-carrier, a ratchet-wheel connected with the said brush, and an actuating pawl 65 engaging said ratchet-wheel, of a pawl-carrier mounted upon a journal of the clearer-brush and ratchet-wheel and engaged with the said stand so that the rocking movement of the stripper-carrier and brush produces movement of the pawl-carrier and pawl which rotates the brush.

6. In a traveling flat carding engine, the combination with a clearer-brush for removing lint from the end-portions of the traveling flats, a ratchet-wheel connected with said clearer-brush, of a brush-support having an open bearing for the brush-journal, a pawl engaging the said ratchet-wheel, and a pawl-carrier having an open bearing fitting said brush-journal, and a bracket or stand having an open slot receiving a projection from said pawl-carrier, whereby the pawl-carrier is vibrated to rotate the brush as a result of the rocking movement of the brush-support.

7. In a traveling flat carding engine, the combination with a clearer-brush for removing lint from the end-portions of the traveling flats, a ratchet-wheel connected with said clearer-brush, a rocking brush-support having an open bearing for the brush-journal, a supporting bracket, and a pawl engaging the said ratchet-wheel, of a pawl-carrier having an open bearing fitting said brush-journal, said pawl-carrier loosely engaging said supporting bracket and thereby actuated to rotate the brush as a result of the rocking movement of the brush-support.

GEORGE F. ALBRECHT.
